UNITED STATES PATENT OFFICE.

JOHN F. O'CONNOR, OF CHICAGO, ILLINOIS, ASSIGNOR TO W. H. MINER COMPANY, OF CHICAGO, ILLINOIS, A CORPORATION OF ILLINOIS.

TANDEM SPRING DRAFT-RIGGING FOR RAILWAY-CARS.

No. 829,727.

Specification of Letters Patent.

Patented Aug. 28, 1906.

Application filed February 16, 1906. Serial No. 301,341.

To all whom it may concern:

Be it known that I, JOHN F. O'CONNOR, a citizen of the United States, residing in Chicago, in the county of Cook and State of Illinois, have invented a new and useful Improvement in Tandem Spring Draft-Rigging for Railway-Cars, of which the following is a specification.

My invention relates to improvements in tandem spring draft-rigging for railway-cars.

The object of my invention is to provide a tandem spring draft-rigging for railway-cars of a strong, simple, efficient, and durable construction which will be compact in form and occupy a comparatively limited amount of space and which may be made of any desired tension or cushioning power without materially increasing the space occupied by it, in which there will be no liability to impart to the springs a permanent set or injury, however great or severe may be the strain to which they are subjected, and which will properly cushion the movements of the draw-bar in both pulling and buffing.

My invention consists in the means I employ to practically accomplish this object or result—that is to say, it consists, in connection with the draw-bar and draw-bar strap and the draft-sills and side plates or stop castings secured thereto, of a reciprocating spring-cage having pockets or chambers to receive each a series of flat spring-plates and a pair of followers, one at the front and the other at the rear of the reciprocating spring-cage, and adapted to abut against the same when the spring-plates are compressed, bent, or deflected to the desired extent, the spring-cage and the followers having concave and convex bearing-surfaces to engage the springs and cause the same to be deflected under the movement of the followers and spring-cage, the convex bearing-surfaces or faces being preferably on the followers and the concave bearing-faces on the spring-cage and two series of straight flat springs fitting in the chambers or pockets of the spring-cage and interposed between the spring-cage and the front and rear followers, respectively.

My invention also consists in the novel construction of parts and devices and in the novel combinations of parts and devices herein shown and described.

In the accompanying drawings, forming a

part of this specification, Figure 1 is a side elevation, partly in central vertical section, 55 of the tandem spring draft-rigging embodying my invention. Fig. 2 is a plan view, partly in horizontal section. Fig. 3 is an enlarged vertical cross-section on line 3 3 of Fig. 1. Fig. 4 is a detail perspective view of the reciprocating spring-cage, and Fig. 5 is a detail perspective view of one of the followers.

In the drawings, A represents the center sills or draft-sills of the framework of a car to which the draft-rigging is applied. A' is the 65 front or cross sill, A² the carry-iron, and A³ the body-bolster or transverse frame-piece at the rear of the draft-rigging.

B is the car-coupler, B' the draw-bar, and B² the draw-bar strap, yoke, or extension secured to the draw-bar in the customary manner by bolts or rivets.

C are the side plates, cheek-plates, or stop-castings of the draft-rigging, the same having front and rear stops or shoulders c c' 75 for the front and rear followers D D' to abut against and being rigidly secured to the center sills or draft-sills of the car by rivets or bolts c². The side plates or stop-castings C have the customary upper integral guides or 80 flanges C' and also lower removable guides C², secured in place by bolts c³, so that upon removal of the lower guides C² the springs, spring cage or box, and followers of the draft-rigging may be easily and conveniently removed and replaced when desired.

F is a movable or reciprocating spring cage or box having front and rear chambers or pockets F' F² to receive the tandem-arranged front and rear series of flat straight springs 90 G G', which are interposed between the spring cage or box F and the front and rear followers D D'.

The front and rear followers D D' each have convex curved bearing-faces d, preferably of 95 a skeleton or web construction, as illustrated in the drawing to engage and bear against the springs G at the middle portion thereof, and the reciprocating spring cage or box F has correspondingly-curved concave bearing-surfaces f, so that the springs G G engage the cage at their ends when the springs are in their straight or unflexed position, as will be readily understood from Fig. 2 of the drawings. While it is immaterial whether the convex spring-engaging faces be on the followers 100 105

or on the spring cage or box, I prefer to make the followers with the convex bearing-faces and the spring cage or box with the concave bearing-faces. The followers D D' are duplicates of each other, as this is a convenience in manufacture, and each is provided with flanges or walls d', which preferably fit within the ends of the spring cage or box F and telescope therewith. The followers also have shoulders d², which abut against the ends of the spring cage or box F and limit the extent of telescoping movement of the followers in respect to the spring cage or box, and the consequent compression or flexure of the springs. Each set or series G G' of straight flat spring-plates are preferably loosely secured together by bolts or rivets g near the middle of the springs, so as not to interfere with their flexure, the bolts serving to hold the springs together and being thus a convenience in handling the springs.

The spring cage or box F, in connection with the series of straight flat spring-plates G and the curved bearing face or wall f of the cage into and against which the springs are flexed, constitutes a closed or air-compression chamber F' or F², in which as the springs are bent by the sudden movements of the draw-bar the air is practically confined and compressed, thus adding materially to the cushioning power of the draft-rigging, as the air can escape from this closed chamber but slowly through the very limited openings or crevices existing between the upper and lower edges of the spring-plates and the upper and lower surrounding walls of the spring box or cage.

I claim—

1. In a draft-rigging, the combination with side plates or stop-castings and the draw-bar and draw-bar strap or extension, of a reciprocating spring cage or box furnished with a pair of chambers or pockets to receive two series or sets of flat straight spring-plates, a pair of followers, said followers and said spring cage or box having coöperating curved bearing-faces engaging the springs, and two tandem-arranged sets or series of flat straight springs interposed in the chambers or pockets of said spring cage or box between it and the followers, substantially as specified.

2. In a draft-rigging, the combination with side plates or stop-castings and the draw-bar and draw-bar strap or extension, of a reciprocating spring cage or box furnished with a pair of chambers or pockets to receive two series or sets of flat straight spring-plates, a pair of followers, said followers and said spring cage or box having coöperating curved bearing-faces engaging the springs, and two tandem-arranged sets or series of flat straight springs interposed in the chambers or pockets of said spring cage or box between it and the followers, said followers

having walls or flanges telescoping with the ends of said spring cage or box, substantially as specified.

3. In a draft-rigging, the combination with side plates or stop-castings and the draw-bar and draw-bar strap or extension, of a reciprocating spring cage or box furnished with a pair of chambers or pockets to receive two series or sets of flat straight spring-plates, a pair of followers, said followers and said spring cage or box having coöperating curved bearing-faces engaging the springs, and two tandem-arranged sets or series of flat straight springs interposed in the chambers or pockets of said spring cage or box between it and the followers, said followers having shoulders abutting against the ends of said spring cage or box to limit the extent of flexure or compression of the springs, substantially as specified.

4. In a draft-rigging, the combination with the draw-bar and draw-bar strap or extension, and side plates or stop-castings having front and rear stops for the followers to abut against, of a reciprocating spring cage or box, a follower and a series of straight, flat springs, interposed between said follower and the spring cage or box, said spring cage or box and the follower having coöperating curved bearing-faces to engage the springs and cause their flexure, substantially as specified.

5. In a draft-rigging, the combination with the draw-bar and draw-bar strap or extension, and side plates or stop-castings having front and rear stops for the followers to abut against, of a reciprocating spring cage or box, a follower and a series of straight, flat springs, interposed between said follower and the spring cage or box, said spring cage or box and the follower having coöperating curved bearing-faces to engage the springs and cause their flexure, and means for connecting said series of straight flat springs together, substantially as specified.

6. In a draft-rigging, the combination with the draw-bar and draw-bar strap or extension, and side plates or stop-castings having front and rear stops for the followers to abut against, of a reciprocating spring cage or box, a follower and a series of straight, flat springs, interposed between said follower and the spring cage or box, said spring cage or box and the follower having coöperating curved bearing-faces to engage the springs and cause their flexure, said side plates or stop-castings having a lower removable guide upon which said spring cage or box and said follower reciprocates, substantially as specified.

7. In a draft-rigging, the combination with the draw-bar, and draw-bar strap or extension, of side plates or stop-castings having front and rear stops for the followers to abut against, of a reciprocating spring cage or box

having a closed or air-confining pocket to receive the springs and a curved bearing-face to engage the springs, a follower having a correspondingly-curved bearing to engage the springs, and a series of straight flat springs interposed between said follower and the spring cage or box and operating to compress the air in the confined chamber of the cage or box as the springs are flexed, substantially as specified.

8. In a draft-rigging, the combination with a spring cage or box having a closed or air-confining chamber into which the springs are flexed, a follower and a series of straight flat 15 spring-plates interposed between the follower and the bearing-face of the spring cage or box

and operating to compress the air in the chamber of the spring cage or box as the springs are flexed, and thus increasing the resisting capacity of the draft-rigging, substantially as specified.

9. A combined air and spring resistance draft-rigging having in combination a spring cage or box, a follower and interposed straight flat springs fitting the interior of 25 said spring box or cage and forming therewith a closed air-chamber, substantially as specified.

JOHN F. O'CONNOR.
